US0D1071971S

(12) **United States Design Patent** (10) Patent No.: **US D1,071,971 S**
(45) Date of Patent: ** Apr. 22, 2025

(54) **DISPLAY SCREEN OR PORTION THEREOF
WITH GRAPHICAL USER INTERFACE**

(71) Applicant: **BIGO TECHNOLOGY PTE. LTD.**,
Mapletree Business (SG)

(72) Inventor: **Jiayun Li**, Mapletree Business (SG)

(**) Term: **15 Years**

(21) Appl. No.: **35/521,200**

(22) Filed: **Apr. 22, 2024**

(80) **Hague Agreement Data**

Int. Filing Date: **Apr. 22, 2024**

Int. Reg. No.: **DM/237342**

Int. Reg. Date: **Apr. 22, 2024**

Int. Reg. Pub. Date: **Jun. 7, 2024**

(57) **CLAIM**

The ornamental design for a display screen or portion thereof with graphical user interface as shown and described.

DESCRIPTION

1. Display screen or portion thereof with graphical user interface

1 : Front

The key features of the design lie in the graphical user interface; the broken line in the reproduction showing a display screen or a portion thereof is for the purpose of illustrating environment and forms no part of the claimed design.

1 Claim, 1 Drawing Sheet
